Primary Examiner — Elizabeth Albert(74) *Attorney, Agent, or Firm* — Seed IP Law Group LLP(57) **CLAIM**

The ornamental design for a compass, as shown and described.

DESCRIPTION

FIG. 1 is a front right perspective view of a compass showing my new design.

FIG. 2 is a rear elevation view thereof.

FIG. 3 is a right side elevation view thereof.

FIG. 4 is a front elevation view thereof.

FIG. 5 is a left side elevation view thereof.

FIG. 6 is a top plan view thereof.

FIG. 7 is a bottom plan view thereof; and,

FIG. 8 is another front right perspective view of the compass shown in FIG. 1.

The broken lines in the figures illustrate environment only and form no part of the claimed design.

1 Claim, 4 Drawing Sheets(56)
